UNITED STATES PATENT OFFICE

134,060

DESIGN FOR A HEARING AID APPARATUS CASE

William D. Penn, Dallas, Tex.

Application August 19, 1942, Serial No. 107,964

Term of patent 3½ years

To all whom it may concern:

Be it known that I, William D. Penn, a citizen of the United States residing at Dallas, in the county of Dallas and State of Texas, have invented a new, original, and ornamental Design for a Hearing Aid Apparatus Case, of which the following is a specification, reference being had to the accompanying drawing, forming a part thereof, in which Fig. 1 is a front elevational

view of a hearing aid apparatus case showing my new design;

Fig. 2 is a side elevational view; Fig. 3 is a top view, and Fig. 4 is a bottom view.

The rear of the device is substantially plain.

I claim:

The ornamental design for hearing aid apparatus case, as shown and described.

WILLIAM D. PENN.
